OVERBED TABLE

Carl W. Sundberg and Montgomery Ferar, Southfield,
Mich., assignors to American Seating Company, Grand Rapids, Mich., a corporation of New Jersey

Filed Sept. 11, 1961, Ser. No. 66,667

Term of patent 14 years

(Cl. D33—14)

Fig. 2

The dotted line indications of portions of a bed in FIGURES 1, 3 and 4 are for illustrative purposes only.

This application constitutes a continuation-in-part of our application Serial No. D-64,068 filed February 27, 1961, and now abandoned.

We claim:

The ornamental design for an overbed table, substantially as shown and described.
